UNITED STATES PATENT OFFICE.

JOHN HANSEN, OF BETTENDORF, IOWA, ASSIGNOR TO DAVENPORT MANUFACTURING CO. INC., OF DAVENPORT, IOWA.

POWER BALING MACHINE.

Application filed June 15, 1925. Serial No. 37,209.

To all whom it may concern:

Be it known that I, JOHN HANSEN, a citizen of the United States, residing at Bettendorf, in the county of Scott and State of 5 Iowa, have invented certain new and useful Improvements in Power Baling Machines, of which the following is a specification.

My invention has reference to power baling machines, and belongs to that type 10 thereof wherein a platen or ram is arranged to be moved vertically by means of a pair of vertical screws and travellers thereon, such as is embodied in my former application for Letters Patent of the United States, filed 15 April 20, 1925, Serial No. 24425.

One of the purposes of the present invention is to provide a machine of comparatively large construction, such as is employed in places where there is a considerable accumulation of paper and other material, and which is so arranged that the material may be fed into the same from an upper floor, if desired.

Another purpose of the invention is to 25 provide a machine of the class mentioned wherein the platen is formed of two parts or leaves, independent of each other, which leaves are arranged to drop downwardly out of the way when the baler is to be provided 30 with material, so as to leave the upper end of the baler entirely clear for the reception of such material.

Another object thereof is to provide a 35 means for holding the platen parts in closed position while the baling operation is being carried on, and which will fully resist the compression force of such operation.

The particular construction, arrangement, 40 and operation of the various parts of the machine will more fully appear from the following specification, reference being had to the accompanying drawings, wherein;—

Fig. 1 is a side elevation of the invention, partly in section, the true proportions 45 not being maintained therein, the length of the machine being somewhat contracted.

Fig. 2 is a plan view thereof, partly in section on the broken line 2—2 of Fig. 1.

Fig. 3 is a cross-section on the broken 50 line 3—3 of Fig. 2.

Fig. 4 is an end view of the platen control devices, with the platen sections in open position.

Fig. 5 is a detail of the platen and supporting frame therefor.

Fig. 6 is an end view of the platen frame and parts supported thereby.

Fig. 7 is a plan view of the platen guiding mechanism, with adjacent parts shown in horizontal section.

Referring first to Fig. 1, the reference number 1 indicates the base of the machine, upon which is supported a floor 2, provided with cross-channels 3 to receive the wires by which the completed bale is bound. Upon said base is supported a frame consisting of corner-posts 4, united near their upper ends by cross-pieces 5, and longitudinal plates 6. Fixed to the cross-pieces 5 are bearings 7, 70 in which are rotatably supported the upper ends of a pair of screw-shafts 8, the lower ends of said shafts being journaled in bearings 9 on cross-plates 10, on the base 1. Fixed on the lower ends of said shafts are 75 volute gear-wheels 11, adapted for simultaneous operation from a common shaft, in the manner shown in said former applica- 80

tion. Interiorly threaded sleeves 12 are vertically movable on the shafts 8, upon said shafts being rotated, and rockingly mounted on said sleeves are supports 13, with which a pair of plates 14 has a pivotal connection. Secured between said plates is a frame 15, 85 having side plates 16. The structure so far described is largely similar to that set forth in said former application.

Supported from the side plates 16 is a platen or compression member, formed of 90 two sections, each consisting of a plurality of plates 17, the plates of each section being capable of swinging downwardly and outwardly by means of a hinged connection of the central ones of said plates with plates 17^a fixed to the plates 16. The plates 17 are preferably formed of pieces of wood of suitable thickness, and are separated by spaces 18, coinciding in position with the channels 3. The inner ends of the plates of the two sections are also spaced, and near said inner ends the plates of each section are united by a cross-plate 19, so that each of said sections will act as a unitary member. 100

Fixed to the plates 17 at one end of the platen is a pair of arms 21, at the upper ends of which are rollers 22, which bear against angle-plates 23 supported vertically in the machine by means of posts 4, con- 110

nected with the main frame. Said arms and rollers serve to hold the platen sections in a horizontal position during the greater part of the movement of such platen. At 5 their upper ends the tracks formed by the plates 23 are bent inwardly as at 25 in Fig. 3, which tracks are followed by the rollers 22, this movement being impelled by the weight of the platen sections, which drop 10 downwardly at the side of the machine, as shown in Fig. 4. This forms an opening through which the material may be fed downwardly into the receptacle of the machine, the upper part of which will be a 15 little below the lower ends of the platen sections 17 when the platen frame is at its highest point. When the receptacle is filled the screws 8 are operated to move the platen frame downwardly again, the rollers 22 moving 20 outwardly along the tracks 25 and bringing the platen sections into a horizontal position again, in which position the work of compressing the material in the receptacle is performed thereby. The upward movement 25 of the platen sections is limited by stops 26 on the inner faces of the end frames 15, with which the ends of the plates 19 contact. (Fig. 2.)

So far as the receptacle is set forth in the 30 drawings herein, one end thereof is shown formed of plates 27, spaced apart at their inner edges, and having said edges reinforced by angle-plates 28, which serve as guides for the arm 14 at that end of the machine. The outer edges of the plates 28 are secured to angle-plates 29, fixed in the frame of the machine. The opposite end 35 of the enclosure is formed of a pair of plates 30, also spaced apart and reinforced by angle-plates 31, forming guides for the arm 14 at that end of the machine. By means of said guides and the pivotal support 40 of the arms 14 the platen frame is permitted a limited freedom of movement in its vertical operations. The plates 30 are projected upwardly for a distance above the angle-plates 6, as shown in Fig. 3, so as to furnish supports for the tracks 25. During the compression operation the 45 rollers 22 move freely along the tracks, the compression stress being received entirely by the platen sections and frame which supports them.

The machine is simple and effective in operation, and the sections of the platen open and close promptly. Adaptations may be made to fit both ends of the platen with the operating devices, if desired, but this is not necessary.

60 What I claim, and desire to secure by Letters Patent, is:

1. A device of the class described, comprising a frame and receptacle therein, vertical screws rotatably mounted in the ends 65 of said frame, travellers on said screws, a

platen frame supported by said travellers, so as to be capable of movement vertically of said receptacle, a platen section hingedly connected with said platen frame, so as to swing downwardly to one side thereof, means 70 for holding said platen section in a horizontal position in its movement in the receptacle and to a point above the same, said means being releasable at said point to permit said section to drop downwardly by 75 the force of gravity.

2. A device of the class described, comprising a frame and receptacle therein, vertical screws rotatably mounted in the ends 80 of said frame, travellers on said screws, a rectangular platen frame supported by said travellers, so as to be capable of movement vertically of said receptacle, a pair of platen sections hinged to the sides of said last-named frame, so as to be capable of dropping 85 downwardly away from each other, means for holding said platen sections in a horizontal position in the movement of the platen frame in the receptacle and to a given point above the same, said means 90 being automatically releasable at said point to permit said sections to drop downwardly from the force of gravity, and returning said sections to their original positions upon 95 said platen frame moving downwardly again.

3. A device of the class described, comprising a suitable receptacle provided with vertical channels in its ends, a rectangular frame movable in said receptacle and provided with extensions movable in said channels, means connected with said extensions for moving said frame vertically of said receptacle, platen sections hinged to the sides of said frame, so as to drop downwardly away from each other, means for holding said sections in closed position during the movement of said frame, releasable upon said frame reaching a predetermined height, permitting said sections to swing downwardly from gravity, and operating to return said sections to a horizontal position upon said frame moving downwardly again. 100

4. A device of the class described, comprising a frame, a receptacle therein, a platen frame movable vertically in said receptacle, and above the same, a pair of platen sections, hinged to the sides of said platen frame, so as to be capable of swinging 105 downwardly away from each other, guiding means for said platen frame in its vertical movements, and cooperating devices comprising tracks on said main frame and engaging members on the platen frame adapted to hold said platen sections in a horizontal position during the movement of said platen frame to a point at the upper 110 end of its movement, at which point said sections are permitted to drop downwardly of their own weight, said parts being capable 115 of

ble of returning said sections to their normal positions upon said platen frame being moved downwardly again.

5. A device of the class described, comprising a main frame and receptacle therein, provided in its ends with guide channels, vertical screws rotatably mounted in the ends of said frame, travellers on said screws, a rectangular frame movable in said receptacle and to a point above the same, having connecting members at its ends pivotally connected with said travellers, and slidably in said guide channels,

one or more platen sections having a hinged connection with said rectangular frame, so as to be capable of swinging downwardly so as to leave said frame unobstructed, tracks on said main frame and cooperating means on said rectangular frame, holding the movable part of the platen normally in closed position, but permitting the opening thereof at the end of the upward movement of the platen mechanism.

In testimony whereof I affix my signature.

JOHN HANSEN.
